UNITED STATES PATENT OFFICE.

GEORGE S. PARKER, OF SALEM, MASSACHUSETTS.

DESIGN FOR A PLAYING-TRACK OF A BOARD GAME.

48,008.

Specification for Design.

Patented Oct. 19, 1915.

Application filed July 22, 1915. Serial No. 41,411. Term of patent 14 years.

all whom it may concern:

Be it known that I, GEORGE S. PARKER, a citizen of the United States, and a resident of Salem, in the county of Essex and State of Massachusetts, have invented a new, original, and ornamental Design for a Playing-Track of a Board Game, of which the following description, in connection with the accompanying drawings, is a specification.

In the drawings the figure is a plan view of a playing track of a board game illustrating my new invention.

I claim:

The ornamental design for a playing track of a board game, as shown.

In testimony whereof, I have signed my name to this specification, in the presence of two subscribing witnesses.

GEORGE S. PARKER.

Witnesses:

LOUIS A. JONES,
IRVING U. TOWNSEND.
